ROBERT A. REYNOLDS, OF PORT HURON, MICHIGAN.

SELF-ADJUSTING GRINDING-DISK.

1,072,033.

Specification of Letters Patent.

Patented Sept. 2, 1913.

Application filed February 27, 1913. Serial No. 750,954.

To all whom it may concern:

Be it known that I, ROBERT A. REYNOLDS, a citizen of the United States, residing at Port Huron, county of St. Clair, and State 5 of Michigan, have invented certain new and useful Improvements in Self-Adjusting Grinding-Disks, and declare the following to be a full, clear, and exact description of the same, such as will enable others skilled 10 in the art to which it pertains to make and use the same, reference being had to the accompanying drawings, which form a part of this specification.

This invention relates to a self-adjusting 15 stationary disk for a grinding machine.

It has for its object structure devised to support the stationary grinding disk so that the stationary disk may accurately and automatically parallel itself with a revolving 20 grinding disk.

In the drawings:—Figure 1, is a side elevation of the grinding machine, the grinding disk housing and hopper being broken away and sectioned. Fig. 2, is a sectional detail of the self-adjusting grinding disk support and adjacent parts.

A, indicates the base of the grinding machine. 1 and 2 represent pillow-blocks that rotatably support the shaft 3. The two 30 bearings are completed by the pillow-block caps 4 and 5. The end of the base A is formed into a grinding disk housing 6 that is closed by a cover plate or stationary grinding disk support 7. The circular 35 opening of the housing 6 is bordered by an annular flange 8 to which the disk support 7 is loosely attached by the screw-bolts 9 which pass through the holes 10 which are considerably larger than the bolts. At 40 attached to the base A by the legs 11, only one of which is shown in the drawings, is the hopper 12 which has a spout portion 13 that passes through the bearing ring 14 and is arranged to slide therein. Spiral springs 45 15 are attached at one end to the hopper 12 and at the other end to the bearing ring 14 so as to act as spacers for these two members. Likewise the springs 16 press against the bolt heads 9 and the stationary disk 50 support 7 tending to thrust the disk support yieldingly into the opening of the housing.

The end of the shaft 3 that lies in the housing 6 has a head that forms a revolving disk support 17. Upon this is supported the revolving disk 18. A com-

panion stationary disk 19 is supported by the stationary disk support 7.

Referring to Fig. 2, it will be seen that the contour of the wall of the housing 6 at its opening appears at 20 in this figure as a portion of a circle. There is an opening in the center of the cover plate or stationary disk support 7 and examination of this opening will show that this appears as a 60 portion of a circle at 21. The contour of these two last mentioned surfaces is in reality a part of a sphere and the circles, upon which the parts of circles, shown in this figure, are struck have a common center at 22. These two surfaces are part-spherical and concentric. Similarly the surfaces of the periphery of both the stationary disk support 7 and the bearing ring 14 are part-spherical and concentric, 65 their center being at 22. This arrangement allows of the tilting laterally of the disk support 7 upon the ring bearing 14.

The hopper 12 is a fixed member and will be so referred to in the claims. The ring 70 bearing 14 is a member slidable with respect to the fixed member and the stationary disk support 7 is capable of a very limited rotation due to the looseness of the bolts 9 in the bolt holes 10 and capable of a 80 limited tilting movement upon the ring bearing 14 and in the part-spherical seat of the housing. The springs 16 and 15 tend to thrust the disk support 7 into its seat and against the revolving disk 18. The 85 revolving disk 18 is thrust toward the stationary disk 19 by the springs 23 that are coiled upon the guide-pins 24 upon which the wedge block 25 slides. A wedge-faced lever 26 is fast to the stub shaft 27 that 90 thrusts upon the thrust-washers 28. These thrust-washers engage with the end of the shaft 3.

It will be understood that by turning the wedge face lever 26 down from the position 95 shown in Fig. 1, that the grinding disks will be brought into closer relation and in working position. When this is done, it may be that the stationary grinding disk is not in an exactly parallel plane with the 100 revolving grinding disk as is desirable for the most efficient grinding, but, inasmuch as the stationary grinding disk is held upon a yieldable support, which is capable of both tilting and limited rotative movement, the 105 stationary grinding disk will be adjusted to exact parallelism with the revolving 110

grinding disk when that member starts to revolve, as it will strike the protruding portions of the stationary grinding disk and cause the stationary grinding disk to assume a position wherein it will not be struck by the rotating grinding disk.

I employ springs to press the stationary disk inward, that are about one and one-half or two times as strong as the springs 10 that thrust the rotating grinding disk toward the stationary grinding disk. The shaft 3 carries a drive pulley 29 which is driven by a belt 30. A belt 31 that connects with the shaft 3 drives a second shaft 32 15 upon which is the feed screw 33 near the mouth of the hopper 12. A second feed screw 34 is fastened to the end of the revolving shaft 3 and tends to convey the grain through an opening in the disk 19.

20 What I claim is:—

1. In a grinding machine, the combination of a rotatable disk, a stationary disk, a stationary disk support therefor provided with a part-spherical periphery, means for yieldingly thrusting the stationary disk into proximity to the rotating disk, a housing provided with a part-spherical seat in which the part-spherical periphery of the stationary disk support fits and a bearing ring provided with a part-spherical and concentric periphery upon which the surface of a complementary concavity at the center of the stationary disk support bears, substantially as described.

35 2. In a grinding machine, the combination of a rotatable grinding disk, a stationary grinding disk, a stationary grinding disk support provided with a part-spherical periphery, a housing provided with a part-spherical seat into which part-spherical periphery of the stationary disk support fits, a bearing-ring provided with a part-spherical periphery that fits into and supports a part-spherical surface at the center of the 40 stationary disk support, the said part-spherical surfaces being concentric and means for yieldingly thrusting the bearing ring toward the rotating disk, substantially as described.

45 3. In a grinding machine, the combination of a rotating disk, a stationary disk in proximity thereto, a stationary disk support pro-

vided with a part-spherical periphery and a part-spherical central hole, a feed hopper having a spout portion protruding through the central hole, a housing provided with a part-spherical seat into which the part-spherical periphery of the stationary disk support fits, a bearing ring slidable upon said feed hopper spout and provided with a part-spherical periphery that fits into the part-spherical central hole of the stationary disk support and means for yieldingly thrusting the bearing ring toward the rotating disk, substantially as described.

4. In a grinding machine, the combination 65 of a housing provided with a part-spherical seat, a rotating grinding disk supported therein, a stationary grinding disk in proximity thereto, a stationary disk support having a part-spherical periphery that fits in 70 the part-spherical seat of the housing, a fixed hopper provided with a spout engaging through a central opening of the stationary disk support, the said stationary disk support being provided also with a central 75 part-spherical cavity, a bearing ring provided with a part-spherical periphery that fits into the part-spherical cavity of the stationary disk support and that is slidable upon the spout of the feed hopper, the said 80 part-spherical surfaces having a common center, and springs spacing the feed hopper and the bearing ring, substantially as described.

5. In a grinding machine, the combination 85 of a part-spherical member, a stationary grinding disk support provided with a part-spherical central aperture that fits over the part-spherical surface of the part-spherical member, a stationary grinding disk attached 90 to the stationary grinding disk support, a rotatable grinding disk supported in face to face relation with the stationary grinding disk and yielding means bearing against the part-spherical member, substantially as de- 95 scribed.

In testimony whereof, I sign this specification in the presence of two witnesses.

ROBERT A. REYNOLDS.
